UNITED STATES PATENT OFFICE.

THOMAS J. GRIFFIN, OF LOS ANGELES, CALIFORNIA.

ROTARY DRILLING-RIG.

1,095,157.

Specification of Letters Patent.

Patented Apr. 28, 1914.

Application filed October 13, 1913. Serial No. 794,839.

To all whom it may concern:

Be it known that I, THOMAS J. GRIFFIN, a citizen of the United States, residing at Los Angeles, in the county of Los Angeles 5 and State of California, have invented a new and useful Rotary Drilling-Rig, of which the following is a specification.

This invention relates to a drilling rig of the rotary type.

10 One of the objects is to provide a screw feed and so combine the parts that the clutches, brakes, and screw feed may all be operated by the driller without moving from his regular position. Former constructions 15 necessitated another person to disengage the rotary clutch and assist in engaging and disengaging the quick hoist.

Another object is to provide for stopping the movement of the quick hoist sprockets 20 and chain, or the rotary table chain and sprockets, either individually or collectively when they are not being used, thereby removing a source of frequent injury to the operators and eliminating wear and noise 25 and saving power. This makes it possible to select and operate the particular gearing needed for the work, without needlessly running the gearing not used.

Another object is to accomplish the control 30 of the gearing with few levers and to provide for engaging and disengaging the quick hoist and engaging and disengaging the rotary table connection, or disengaging both with a single lever. Heretofore the engine 35 has been provided with sprockets of various sizes and to change the speed of the drum for quick hoisting or slow hoisting the chain had to be removed and changed to another sprocket on the engine, all of which 40 is avoided by the present construction, which enables the speed of the drum to be instantly changed from slow hoist to quick hoist or vice versa, by simply shifting a lever.

45 Another object is to dispense with the clutch on the rotary table.

Another object is to enable both brake bands to be operated simultaneously by the driller alone without an assistant. Heretofore 50 the driller could only operate one brake and when in handling heavy strings of pipe and the second brake was needed, it was necessary to have an assistant to operate it.

Another important object is to provide a 55 screw feed to perfectly control the downward feed of the drill pipe. Heretofore a

screw feed has been occasionally employed on a light drilling rig, but it could not be used on rigs of larger type for heavier duty because the engagement and disengagement 60 of such screw feed required considerable time, which was dangerous because of the liability of the drill pipe slipping down before the driller could get his brake set. The great weight of the drill pipe demands a 65 powerful and quick acting device to hold it and in changing the support from the brake to the screw feed or vice versa, the operation must be instantaneous to prevent the pipe dropping, and the present invention 70 provides for instantaneously throwing the screw feed into or out of operative sustaining relation to the drill pipe, thereby entirely obviating the previous difficulty, and making it possible to employ a screw feed 75 in heavy duty with all its attendant advantages. In heavy work during drilling operation with rigs heretofore used, the driller had to constantly hold the brake lever, and the jar and rotation of the rig constantly 80 tends to loosen the brake, and it is a frequent occurrence for the drill pipe to slip and drop owing to this reason, even when the driller is holding the brake. When the drill pipe thus drops the drill rigidly engages 85 the formation and frequently before the driller can stop the engine, it has twisted the drill pipe off down in the hole. With the screw feed as herein provided the driller has perfect control of the lowering of the 90 drill pipe and the pipe cannot accidentally slip and drop. As the screw does not have to be turned constantly to feed the drill pipe except when going through very soft formation, but only needs occasional turning, the 95 driller is free much of the time to move about on the rig and is enabled to attend to any other duties without stopping the drilling operation.

Another object is to throw the screw feed 100 and slow hoist gearing into or out of operation with a single lever.

Referring to the drawings: Figure 1 is a front elevation of the draw works, the floor 105 of the derrick being shown in section. Fig. 2 is a side elevation of the mechanism shown in Fig. 1. Fig. 3 is an elevation of the opposite side of the screw feed partly in section on line x^3-x^3 in Fig. 1. Fig. 4 is a plan view of the mechanism shown in Fig. 110 1. Fig. 5 is a view similar to Fig. 1, showing a modified form. Fig. 6 is a side eleva-

tion on a reduced scale of the mechanism shown in Fig. 5. Fig. 7 is a side elevation on an enlarged scale of the modified form of screw feed, showing the screw engaging with the worm wheel. Fig. 8 is a view similar to Fig. 7, showing the screw released from the worm wheel. Fig. 9 is a perspective of the screw supporting block.

Referring to Fig. 4, showing the preferred form, 1 designates the rotary table mechanism in general, and 2 designates the rotary draw works. The rotary table mechanism 1 is provided with the usual table 3, having a pipe gripping device 4, the particular construction of which has no bearing on the present invention. 5 is the shaft having a pinion *a* meshing with a gear *b* on the table for operating the table, and the shaft 5 has a fixed sprocket 6, which is driven by a chain 7. Splined on the shaft 5 is a grooved collar 8, having a locking clutch member 9, which is adapted to be interlocked with a stationary male locking clutch member 10, which may, if desired, be a part of the bearing 11 as shown. The collar 8 is engaged by a fork 12, which projects from a shaft 13, operated by a hand lever 14, the shaft 13 being mounted in suitable bearings 15. When the table 30 is stationary, and it is desired to lock the same against rotation the lever 14 may be shifted to engage the clutch member 9 with clutch member 11, thereby positively locking the shaft 5 from rotation.

35 The chain 7 is driven by a sprocket 16 loosely mounted on a counter shaft 17 of the rotary draw works, the shaft 17 being journaled in bearings 18. The shaft 17 is driven by means of a chain 19 operated by 40 the engine, not shown, the chain 19 engaging a sprocket 20 fixed on shaft 17. In the operation of the rig, the counter shaft 17 is constantly revolved, and through the medium of chain 7, the rotary shaft 5 is operated when desired. Heretofore, in rotary rigs the chain 7 has always constantly operated with the counter shaft 17, and in order to stop the rotary table 3, it was necessary to disengage the operative driving relation of the chain with respect to the rotary shaft 5. As the rotary table was located some distance from the draw works, it necessitated the driller moving from his proper position at the draw works over to the table to do this, or calling an assistant to do it for him. Moreover, the constantly running chain 7, which extended directly across the floor of the derrick, was a constant menace to the safety of the workmen, and many serious accidents have been caused by workmen accidentally coming in contact with it, it being especially dangerous on account of its proximity to the workmen constantly on the floor of the derrick when working with the tongs on the

casing, for the chain 7 is right in the way. In the present invention, these objections are overcome. I provide a mechanism whereby the rotation of the chain 7 is stopped whenever the rotary table 3 is to be stopped, when desired, and this makes it perfectly safe for the workmen operating on the casing when the table is not rotated. Another great advantage is that by stopping the rotation of the chain, noise and wear is eliminated, and no power is wasted. In order to stop the operation of the chain 7, I provide a clutching means, which consists of a male clutch member 21 preferably formed as part of the hub of sprocket 16, and a female clutch member 22 is arranged to slide with a feather on counter shaft 17. The clutch member 22 is operated by a lever 23 pivoted at 24 and connected by a link 25 with a hand lever 26 pivoted at 27. By operating hand lever 26, the clutch lever 22 may be instantly engaged or disengaged from clutch member 21, and thereby cause the sprocket 16 and chain 7 to operate or cease operation, as desired.

28 designates the drum, which is rigidly mounted on shaft 29 journaled in bearings 30. The drum 28 is provided with flanges 31, and around the respective flanges 31 are brake bands 32 and 33, one end of each brake band being rigidly connected to a shackle 34, and the other end of brake band 33 is connected to a crank 35 on a brake shaft 36, while the other end of brake band 32 is connected with a crank 37 on the brake shaft 36. The brake shaft 36 is operated by a hand lever 38, which is arranged close to the hand lever 26 before referred to. The driller by operating the single lever 38 may apply both brake bands 32 and 33 simultaneously, thereby securing double the effective braking surface. Heretofore the two brake bands have been independently operated, the driller having to call an assistant whenever both brake bands were to be applied. The present construction enables the driller, himself, to handle both brakes without an assistant, thereby giving him a much more perfect control over the operation. The shackles 34 are adjustable, thereby making it possible to take up for any difference in wear or spring, and cause a uniform pressure of both brake bands when the lever 38 is operated.

The drum 28 is used for lifting the casing and for controlling the lowering of the casing. It is desirable that the drum be capable of operating at different speeds in order to economize time in raising the casing, because of the number of joints of casing being lifted, and its corresponding weight varying. Therefore, when the greatest weight of casing is being handled, a slower hoisting movement is required, while as the number of joints decreases, and the weight

lightens, the hoisting speed should be increased. Heretofore these different speeds of the drum have been secured by a plurality of sprockets on the engine shaft, and by throwing off chain 19 from one sprocket, and placing it on another to change the speed. Such operation was cumbersome, and time was lost in doing it. Moreover, it necessitated shutting down the engine, and 10 tramping over the engine by hand to take off the chain. All of these objections are removed by the present invention, in which only one sprocket is required on the engine, and the chain 19 is constantly driven thereby, and the counter shaft 17 is given a regular uniform movement without stopping the engine, or changing the speed of the drum 28.

A sprocket 39 is rigidly secured to shaft 29, and is connected by a chain 40 with a sprocket 41 loosely mounted on shaft 17, and having a clutch member 42, which is adapted to be engaged by the clutch member 22 previously referred to, the latter being formed as a double clutch member for this purpose, so that by operating lever 26 in one direction, the clutch member 22 may be slid into engagement with sprocket 41 to cause the latter to rotate in unison with the counter shaft 17, and thereby through the medium of chain 40, impart rotation to shaft 29 and drum 28, at a speed corresponding to the relative size of sprockets 41 and 39. In the present embodiment these 30 sprockets are designed to give a relatively quick hoisting speed to the drum 28, while by swinging the lever 26 in the opposite direction, the clutch member 22 may be engaged by the sprocket 16 to cause the latter 40 to rotate with the shaft 17, and thereby drive the rotary table, or by swinging lever 26 into central position, the clutch member 22 may be moved into neutral position between both sprockets 41 and 16, so that 45 neither of them are operative. These three functions are thus controlled by a single lever, and as will be hereinafter shown, it is never desired to operate the drum 28 by the quick hoisting gearing at the same time that 50 the table is being rotated.

Loosely mounted on the shaft 29 is a large sprocket 43, which is connected by a chain 44 with a small sprocket 45 rigidly mounted on the counter shaft 17. The hub of 55 sprocket 43 is formed with a male clutch member 47, which is adapted to be engaged by a female double clutch member 48, which is splined on the drum shaft 29, and is operated by a leg lever 49 pivoted on a stationary vertical shaft 50, supported by a bracket 52. By shifting lever 49 to the right the clutch member 48 may be engaged 60 with the sprocket 43 to cause the latter to rotate drum shaft 29, and impart a relatively slow rotative movement to the drum 65

28. By swinging leg lever to the left it disengages clutch member 48 from sprocket 43, and stops driving drum shaft 29.

Loosely mounted on drum shaft 29 is a worm wheel 53, which is engaged by a screw 54 on shaft 55 operated by hand wheel 56. The shaft 55 is journaled in a bracket 57 rigidly secured to the derrick frame 58. The bracket 57 may be constructed in two parts as shown. In the present form the screw 54 is constantly in engagement with worm wheel 53, and the latter is given an operative driving relation with the shaft 29 by means of the double clutch member 48 when the latter is shifted to the left by lever 49. When the parts are in position shown in Fig. 1, the shaft 29 may be revolved through either quick or slow hoist gearing, or by the unwinding movement of drum 28 by the weight of the casing. Upon engaging clutch 48 with worm wheel 53, the drum 28 is stopped, on account of engagement of screw 54 with worm wheel 53, and rotation of the shaft 29 and drum may be controlled to any desired speed by rotating the hand wheel 56, the 90 brake 38 having been released.

The operation of the rig may be briefly stated as follows: In commencing the operation it will be assumed that the drill pipe is to be withdrawn from a previously drilled hole of considerable depth, in order to replace the drill. This frequently has to be done. Then it will be assumed that the new drill has been put on, and the string of tubing is to be replaced, and the drilling recommenced. It will be understood that the drill pipe is connected through the usual cable and blocks with the drum 28. The driller swings over lever 49 and clutches sprocket 43 with shaft 29, thereby imparting a slow and powerful hoisting rotation to the drum 28. He then releases brake lever 38 to throw off the brakes 32 and 33, and the drum 28 hoists the string of pipe the required distance to enable a stand which is 110 the length of pipe to be unscrewed. As soon as this height is attained, the brake lever is applied. The lever 49 is then operated to unclutch the sprocket 43, and the string of pipe is held in suspension only by the brakes 115 32 and 33 long enough to apply an elevator or other sustaining means. Then the driller releases his brake lever, relieving the strain to the drum 28, and the tongs are then operated to unscrew the stand of pipe, and after 120 the stand of pipe has been unscrewed, the driller swings lever 49 to again clutch sprocket 43 to shaft 29, and the slow hoist then raises the stand of pipe which has been unscrewed a few inches, or enough to clear 125 the string of pipe below it, and the driller then applies his brake and then operates lever 49 to unclutch sprocket 43, and the string of pipe is then eased down to rest on the derrick floor by manipulating the brake 130

lever 38, so that the elevators can be disengaged therefrom from the top end of the stand of pipe. Then the driller releases his brake to permit the blocks to lower, and connects to the elevator, which has been previously applied to the string, and then the slow hoist gearing is again operated to lift the string in the manner previously described, and the next stand is disengaged in like manner. This operation is repeated until the string of pipe has become sufficiently light to allow the quick hoist gearing to be used for lifting it, and at such time the operation is the same as before, except that instead of operating lever 49, the driller operates lever 26, and employs the quick hoist gearing, consisting of sprockets 39, 41 and chain 40. After the new drill has been applied, the string is to be placed in the hole for drilling. The driller operates the quick hoist to raise the block and tackle to the top of the derrick, and the upper end of the stand is attached, and then lowered down into the hole in this way, the descent being controlled by the brake, and as soon as the first stand is down its length, it is supported in position by the table or other means, and then the second stand is picked up and placed in position over the first stand and screwed thereto, and then the string thus formed of two stands is lifted either by the slow hoist or quick hoist gearing a few inches in order to disengage the supporting means. Then the brake is applied and the hoist disengaged and the string allowed to descend under the control of the brake. In like manner the succeeding stands are applied to the string, and when the length of the string increases so that it is very heavy the slow hoist gearing is employed each time to lift the string the few inches necessary for the disengagement of the supporting means. When the string has reached the bottom of the hole, it is held there by means of the brake, and lever 26 is operated to engage sprocket 16 with shaft 17, and thereby start the rotary table, and as the drill pipe is thus operated by the table, the drilling proceeds and the drill pipe descends at a rate controlled by the brake, which is manipulated by the driller. As the drill gets to work and in a hard formation, then lever 49 is operated to engage clutch 48 and to lock shaft 29 to the worm wheel 53, and at this time the driller releases the brake entirely and the weight of the pipe is carried by the engagement of the worm wheel 53 with screw 54. The driller can then regulate the descent of the pipe by turning the hand wheel 56 and operating screw 54 to either lower or raise the pipe as desired. The screw is so powerful that it is possible to raise the string of pipe with it if desired. In drilling the driller does not have to constantly keep his hand on the

wheel 56, as it need only occasionally be turned, and this gives him a better opportunity to move about the derrick to tend to other necessary duties without calling assistance. Thus, if the driller finds it necessary to leave the rig without any one in charge, he can readily do so by throwing lever 49, which will act to positively hold the entire string, through the medium of the worm wheel and screw, and it will remain held in this position until released, or the screw is turned. This is a positive sustaining means, making it impossible for the pipe to slip or drop the drill into a crevice or overfeed, eliminating the danger of twisting off the pipe thereby. It will now be readily seen from the foregoing that it is never necessary to operate the quick hoist gearing simultaneously with the table, and that by means of a single lever the driller can perfectly control the rig without any assistant. In operating the feed screw 54 and worm 53 in feeding down the pipe in drilling, it is necessary that the clutch 22 be engaged with sprocket 16 to drive the table to rotate the drill pipe, and therefore the clutch 48 which controls the screw feed must be operated by lever 49, which is independent of the lever 26, which controls clutch 21, and these two levers must thus be operated to produce this coöperative gearing relation throughout the rig, but it is also possible to independently operate the lever 49 to cause the screw feed to be operative even when the table is not rotating, in order to secure the advantage of being able to sustain the pipe when the pipe is not being rotated as above pointed out, and without requiring the application of the brakes in order to make it possible for the driller to move about. It will be observed that the parts are so interrelated and combined in this invention that it is possible to place all of the operating levers or instrumentalities in a group, and thereby at the instant command of the driller. Certain broad features of my invention are also applicable with advantage to rigs of cheaper construction adapted for use on shallow wells or light work, when a two speed hoist is not required. In Figs. 5 to 9 inclusive, I have shown a modified form, in which the screw feed, rotary table control are employed in such a rig. The construction is very similar to the preceding, and it will only be necessary to point out the difference. In the modified form 16^a is the sprocket which drives the table, this being clutched or unclutched from the counter shaft 17^a by a hand lever 26^a through the medium of a mechanism precisely similar to the foregoing. The brakes are operated independently by respective brake levers 38^a, 38^b, which respectively operate cranks 35^a, 37^a, to which the brake bands 32^a, 33^a are connected. Sprocket 20^a is connected with 130

the engine and sprockets 43^a, 45^a and chain 44^a constitute the hoist gearing for driving the drum 28^a. 53^a is the worm wheel engaged by the screw 54^a, the latter in this form being mounted on a bracket 57^a, which is pivoted at 57^b to the stationary bracket 57^c. The screw 54^a may be thrown into or out of mesh with the worm wheel 53^a by tilting it as indicated in Fig. 8.

10 In either form of the invention, on each end of the counter-shaft 17 is a cat head 62 for light hoisting, such as lifting the heavy tools about, around the derrick, etc. In operating either of the cat heads 62, both 15 hoist gearings are disconnected so that the drum is not operated.

What I claim is:—

1. In a rotary drilling rig, a rotary table, a rotary table shaft, means for driving the 20 rotary table from the shaft, a counter-shaft, a sprocket loosely mounted on the counter-shaft, a sprocket rigidly mounted on the rotary table shaft, a stationary clutch member, a clutch member splined on said 25 rotary table shaft, a lever for engaging the latter clutch member with the first clutch member to lock the table, a chain connecting said sprockets, and means for clutching said first sprocket with the counter-shaft.

30 2. In a rotary drilling rig, a rotary table, a rotary table shaft, means for driving the rotary table from the shaft, a counter-shaft, a sprocket loosely mounted on the counter-shaft, a sprocket rigidly mounted on the 35 rotary table shaft, a chain connecting said sprockets, means for clutching said first sprocket with the counter-shaft, a drum shaft, a drum rigid thereon, means for driving the drum shaft from said counter-shaft, 40 a worm wheel loose on the drum shaft, a screw engaging the worm wheel, and a clutch for engaging the worm wheel with the drum shaft to enable the drum to be manually controlled by the screw feed to feed the drill 45 pipe while the rotary table is operating, said worm and screw also being operable to positively prevent rotation of the drum to sustain the drill pipe when said first sprocket is unclutched from the counter-shaft and the 50 table is stationary.

3. In a rotary drilling rig, a rotary table, a drum, and means controlled by a single lever for rotating the drum or for rotating the table.

55 4. In a rotary drilling rig, a rotary table, a drum, and means controlled by a single lever for rotating the drum or for rotating the table, or for releasing both table and drum.

60 5. In a rotary drilling rig, a rotary table, a drum, a counter-shaft, gearing between the counter-shaft and table for driving the table, gearing between the counter-shaft and drum for driving the drum, and means for ren-

dering either of said gearings stationary 65 while the other operates.

6. In a rotary drilling rig, a rotary table, a drum, a counter-shaft, gearing between the counter-shaft and table for driving the table, gearing between the counter-shaft and drum 70 for driving the drum, and means for rendering the first gearing stationary to permit the drum to rotate independent thereof.

7. In a rotary drilling rig, a counter-shaft, a rotary table, a drum, gearing between the counter-shaft and drum for rotating the drum, gearing between the counter-shaft and table for rotating the table, a cat-head on said counter-shaft, and means for rendering both said gearing stationary while 80 the counter-shaft and cat-head rotate.

8. In a rotary drilling rig, a drum, a counter-shaft, gearing for driving the drum from the counter-shaft, two brake bands for engaging the drum, a lever, means operated 85 by said lever for actuating both brake bands, another lever adjacent the first lever, and means operated by the second lever for controlling said gearing.

9. In a rotary drilling rig, a drum shaft, 90 a drum thereon, a worm wheel, a screw engaging the worm wheel, a brake for controlling the rotation of the drum, and a clutch for connecting said worm wheel with the drum shaft to control the drum by the 95 screw when the brake is released, and to disconnect the worm wheel from the drum shaft when the brake is operated.

10. In a rotary drilling rig, a drum shaft, a drum thereon, a worm wheel loose on said 100 drum shaft, a screw engaging said worm wheel, and a clutch for engaging and disengaging said worm wheel with said drum shaft.

11. In a rotary drilling rig, a drum shaft, 105 a drum rigid thereon, a worm wheel loose on said drum shaft, a screw engaging the worm wheel, a sprocket loose on the drum shaft, a counter-shaft, a sprocket on the counter-shaft, a chain connecting said sprockets, a 110 lever, and means operated by said lever for engaging either the worm wheel or first sprocket with said drum shaft, or disengaging them both from said drum shaft.

12. In a rotary drilling rig, a drum shaft, 115 a drum rigid thereon, a worm wheel loose on the drum shaft, a counter-shaft, a sprocket rigid on the counter-shaft, a sprocket loose on the drum shaft, a chain connecting said sprockets, the first sprocket having a clutch 120 member, the worm wheel having a clutch member, a double clutch member splined on the drum shaft between said clutch members, and a lever for operating the double clutch member.

13. In a rotary drilling rig, a counter-shaft, a drum shaft, a drum on the drum shaft, a fixed sprocket on the counter-shaft,

a loose sprocket on the drum shaft, a chain connecting said sprockets, a clutch for engaging the loose sprocket with the drum shaft, a lever for operating said clutch, a 5 sprocket loose on the counter-shaft, a sprocket fixed on the drum shaft, a chain connecting said sprockets, a clutch for engaging the latter loose sprocket with the counter-shaft, and a lever for operating the latter clutch.

10 14. In a rotary drilling rig, a counter-shaft, a drum shaft, a drum on the drum shaft, a fixed sprocket on the counter-shaft, a loose sprocket on the drum shaft, a chain connecting said sprockets, a worm wheel 15 loose on the drum shaft, a screw engaging said worm wheel, a clutch for engaging the loose sprocket or said worm wheel with the drum shaft, a lever for operating said clutch, a sprocket loose on the counter shaft, 20 a sprocket fixed on the drum shaft, a chain connecting said sprockets, a rotary table shaft, a rotary table driven by the table shaft, a sprocket rigid on the table shaft, another loose sprocket on the counter-shaft, 25 a clutch for engaging the latter loose sprocket or the former loose sprocket, with

the counter shaft, and a lever for operating the latter clutch.

15. In a rotary drilling rig, a counter-shaft, a drum shaft, a drum on the drum shaft, a fixed sprocket on the counter-shaft, a loose sprocket on the drum shaft, a chain connecting said sprockets, a clutch for engaging the loose sprocket with the drum shaft, a lever for operating said clutch, a 30 sprocket loose on the counter-shaft, a sprocket fixed on the drum shaft, a chain connecting said sprockets, a rotary table shaft, a rotary table driven by the table shaft, a sprocket rigid on the table shaft, another loose sprocket on the counter-shaft, a clutch for engaging the latter loose sprocket with the counter-shaft, and a lever for operating the latter clutch.

In testimony whereof I have hereunto set 45 my hand at Los Angeles, California, this 6th day of October, 1913.

THOMAS J. GRIFFIN.

In presence of—

GEO. T. HACKLEY,
LORRAINE E. DURROW.
